UNITED STATES PATENT OFFICE

LLOYD W. MOULTON, OF SYRACUSE, NEW YORK, ASSIGNOR TO GAYLORD BROS., INC.,
OF SYRACUSE, NEW YORK, A CORPORATION OF NEW YORK

PRINTING MACHINE

Application filed September 23, 1929. Serial No. 394,531.

This invention relates to a printing machine adapted to be used more particularly in public libraries for keeping records of the different borrowers of books and other matter issued by the libraries as temporary loans and also for recording the dates of issue and return of such books or other matter to and from the borrower, but obviously the machine may be used for many other purposes where temporary loans of articles are made to borrowers for identifying the borrower and recording the dates of issue and return of such articles.

The main object is to provide a simple, compact and durable machine of this character whereby the identification records and date records may be more expeditiously and effectively impressed upon the record cards than has heretofore been practiced.

In other words I have sought to provide a conveniently portable machine whereby the identification records and date records may be made on two separate cards in one and the same operation.

Another object is to provide means whereby the identification character and date of issue or return of the borrowed article may be simultaneously impressed upon the same record card in alinement with each other.

Another object is to provide means whereby the record card or cards may be advanced in the machine, one line spaced at a time following each printing operation.

A further object is to provide an adjustable carrier for a plurality of removable date printing plates capable of being removed and replaced by different type plates and at the same time to permit the carrier to be adjusted endwise for bringing any one of the type plates into alinement with the identification type plate so that any one of different dates of borrowing or return may be recorded upon a card opposite the identification impression.

Another object is to provide a housing for the various moving parts with a movable lid or cover upon which certain parts of the printing mechanism are mounted and to cause said lid or cover to be automatically

locked in its closed position during the normal printing operation of the machine.

Other objects and uses relating to specific parts of the machine will be brought out in the following description.

In the drawings:

Figure 1 is a perspective view of a library-card-printing machine embodying the various features of my invention, the carrier for the date plates and its adjusting means being shown in their starting positions.

Figure 2 is a detailed sectional view showing the operating means for the carrier for the date plates and the stop-pawl cooperating with the shift lever for controlling the opening of the lid, taken in the plane of line 2—2, Figure 6, except that the lid is closed.

Figure 3 is an enlarged detailed sectional view showing the means for locking and releasing the lid in and from its closed position, taken in the plane of line 3—3, Figure 2.

Figure 4 is a detailed sectional view taken in the plane of line 4—4, Figure 2.

Figure 5 is a transverse vertical sectional view taken in the plane of line 5—5, Figure 7.

Figure 6 is a horizontal sectional view taken in the plane of line 6—6, Figure 5.

Figure 7 is a longitudinal vertical sectional view of the same machine taken in the plane of line 7—7, Figure 1.

Figures 8 and 9 are transverse vertical sectional views taken respectively in the plane of lines 8—8 and 9—9, Figure 7.

Figure 10 is an enlarged vertical sectional view through the carrier for the date type plates and guide therefor together with two of the cards in position to be printed by the date type.

Figure 11 is a similar enlarged vertical sectional view through the carrier for the identification type plate and guide therefor together with the same cards shown in Figure 10, portions of the platens being shown in section in both Figures 10 and 11.

As illustrated, this machine comprises a case or housing including a hollow base section —1— and a movable top section or lid —2— which is hinged at —3— along its rear edge to the adjacent portion of the top of the

base section —1— to permit the lid to swing upwardly and rearwardly from its closed position as shown more clearly in Figures 1, 5, 8 and 9.

5 The bottom of the base section —1— is provided with suitable feet —4— of rubber or equivalent material adapted to rest upon the surface of a table or equivalent support, the upper open side of the base being inclined downwardly from its rear edge for supporting the lid —2— in a corresponding inclined plate when in its closed position.

A portion of one of the end walls of the base section —1— is cut away from the top 15 downwardly to form a recess —5— which is adapted to receive a portion of the shifting mechanism for the date plate carrier which is mounted upon the lid —2— and will be hereinafter more fully described.

20 The base section —1— is substantially rectangular in top plan and is adapted to receive and support the platen elements of the printing mechanism together with the actuating means for the platens hereinafter more 25 fully described, the remaining portions of the printing mechanism being mounted upon the lid to move therewith. A keeper plate —6— is mounted upon the inner face of one of the end walls of the base section —1— to 30 form a part of a lid rocking mechanism hereinafter described.

Platen action

35 A pair of opposed upright platen-jaws —7— and —7'— are journaled at their lower ends upon a lengthwise bearing shaft —8— within the housing section —1—, said shaft being mounted in suitable openings in opposite ends of the base section —1— near the bottom and substantially midway between the front and rear walls thereof, shown more clearly in Figure 9.

The platen-jaws extend upwardly from the shaft —8— to a plane just below the top wall 45 or lid —2— and are provided near their upper ends with resilient platens —9— of soft rubber or equivalent material seated in sockets in the inner or adjacent sides of the jaws equal distances from the axis of the shaft 50 —8— to cooperate with interposed type plates for making impressions of the type upon the cards.

The inner face of each of the platens —9— is divided by a transverse recess —10— to 55 form separate platen sections —11— and —11'—, the platen sections —11— being adapted to cooperate with the dating type while the sections —11'— are arranged to cooperate with the identification type for reproducing the impressions of the type-plates 60 upon the card when the platen-jaws are closed.

One of the platen-jaws as —7— is made in the form of a bell-crank lever having a rearwardly projecting arm —12— carrying at its

rear end a roller —13— for engagement with the underside of a cam —14— which is secured to a transversely extending rock shaft —15— and is adapted to engage a roller —16— on the rear side of the jaw —7'— as 70 shown more clearly in Figure 9.

The roller —16— is mounted on the jaw —7'— between the pivotal bearing —8— and corresponding platen —9— so that when the cam shaft —15— with the cam —14— thereon is rocked in the direction indicated by arrow —X— the jaws will be forced to their printing positions against the action of a retracting spring —17— which serves to automatically open the jaws and incidentally to 80 hold the rollers —13— and —16— in contact with opposite faces with the cam —14—, Figure 9.

The cam shaft —15— is journaled in suitable bearings —18— on the base section —1— 85 parallel with the shaft —8— and extends through one of the end walls thereof, its outer end being provided with a hand crank —19— by which it may be rocked about its axis.

Printing mechanism

I preferably employ two type carriers as —20— and —21— actively arranged side by side lengthwise of and between the platen-jaws —7— and —7'— with their type in alinement with each other and with the platen sections —11— and —11'—, the carrier —20— being provided with a plurality of, in this instance four, type plates —22— 100 for impressing upon one or more cards the date of issue or date of return of the borrowed article while the type carrier —21— is provided with a single type plate —23— for impressing upon the card or cards the identification number or other character of the borrower.

The type of both of the carriers are adapted to be simultaneously impressed upon the card or cards in alinement with each other by the closing movement of the jaws —7— and —7'— through the medium of an inking ribbon or equivalent transfer member presently described.

Suitable means is provided for guiding the type carriers —20— and —21— when inserted into the machine between the normally spaced platen jaws —7— and —7'—, said guiding means being preferably mounted upon the lid —2— to move therewith as the lid is opened and closed.

For this latter purpose a pair of guide bars —24— are mounted at their ends upon longitudinally spaced brackets —25— just above the lid —2—, said bars being arranged in parallel spaced relation lengthwise of the machine and extended beyond opposite ends of the jaws —7— and —7'— with the intervening space in alinement with the space between the jaws, the brackets —25— being 125

secured to the lid by screws or other suitable fastening means.

The lid —2— is provided with a lengthwise guide opening —26— for receiving the type carriers —20— and —21— and cards as —a— and —a'— to be printed and also for receiving additional guide plates —27— which are arranged in transversely spaced relation with their upper ends secured in radial slots in the lower inner sides of the bars —24— and their remaining portions extending into the interior of the base section —1— between the platen sections —11— and —11'— of the jaws —9— as shown more clearly in Figures 9, 10 and 11 to assist in guiding the carriers —20— and —21— and holding the same in operative position during the printing operation.

The guide opening between the bars —24— and also between the guide plates —27— is divided by a partition —28— into two separate passages —27'— and —27''— as shown more clearly in Figures 1 and 7, the lefthand passage being adapted to receive the type carrier —20—, Figure 10, while the righthand passage serves to receive the type carrier —21—, Figure 11.

The lefthand passage —27'— is open at the bottom to permit the passage of the lower end of the type carrier —20— therethrough but the passage —27''— for the carrier —21— is preferably closed at the bottom to form a stop —29— for engaging the lower end of the carrier —21— and limiting the downward movement thereof, see Figure 11.

This stop —29— is formed by uniting the lower edges of the guide plates —27— across the intervening passage —27''—. The upper end of the partition —28— is secured to and between the guide rods —24— and extends downwardly therefrom to a point slightly above the stop —29— shown in Figure 7, and also assists in guiding the type plate —20— in its vertical movement.

A similar partition or outer end guide —28'— is secured at its upper end to the guide rods —24— to extend downwardly therefrom between the guide plates —27— and together with the partition —28— assist in guiding the carrier —21— in its vertical movements in the passage —27''—.

The guide passage —27'— for the type carrier —20— is of approximately the same width as the portion of the type carrier passing therethrough while the passage —27''— for the type carrier —21— is considerably wider than the passage —27'— and corresponds approximately to the width of the carrier —21— which, in this instance, is of about the same width as the cards —a— and —a'— to be printed for convenience of manufacture of the cards and carrier —21—.

The lid —2— is provided with additional guide members —30— secured to and projecting upwardly from the upper face of the

lid in spaced relation to the lefthand end bracket —25— a distance corresponding approximately to the width of the cards —a— and —a'— to be printed, said guide members —30— being located at the outer sides of and adjacent the guide rods —24— to cooperate with the lefthand bracket —25—, Figure 1, for guiding the cards —a— and —a'— in their vertical movements through the corresponding portion of the guide opening —26—, said cards being inserted through the openings across the outer faces of the rods —24— as shown in Figures 10 and 11.

The type carrier —20— is preferably made of sheet metal and is provided with a lengthwise opening —22— therethrough of sufficient length to receive a plurality of, in this instance, four of the type plates —22—, said carrier being provided with opposite lengthwise guides —31— forming the opposite walls of the opening for receiving the adjacent edges of the type plates —22— and holding them in operative position against lateral displacement, said type plates being arranged edge to edge so that when placed in operative position the upper edge of the upper plate will engage the top of the opening —22'— while the lower edge of the lower plate will be engaged with a stop shoulder —22''—, Figure 7, to cooperate with the upper wall of the opening —22'— for holding the type plates against vertical displacement.

These type plates are preferably made of thin type metal having date type embossed thereon for making corresponding impressions upon the cards —a— and —a'— when the latter are placed in position for printing and the jaws —7— and —7'— are brought to their printing positions, said type plates being sufficiently resilient to permit the lower plate to be sprung out of engagement with the stop —22''— when it is desired to remove the plates from the guides —31— by endwise displacement after which the removed plates may be replaced by other type plates bearing different dates.

In order that both cards —a— and —a'— may be printed simultaneously each type plate —22— is provided with two rows of similar type, one above the other and embossed in opposite directions so that when the jaws —7— and —7'— are brought to their printing positions corresponding impressions will be made upon outer faces of both cards.

The type plate —23— of the carrier —21— is made of thin type metal and secured in an opening in said carrier in a manner somewhat similar to that shown in my pending application, Serial No. 394,530, filed September 23, 1929, said plate —23— being provided with two rows of type arranged one above the other and embossed in opposite directions so as to produce simultaneous impressions

thereof upon the cards $-a-$ and $-a'$ when the jaws $-7-$ and $-7'$ are brought to their printing positions, these latter impressions being made simultaneously with those from the type plate $-22-$ during the same operation of the platen jaws.

The type plate $-23-$ is preferably secured to the lower lefthand corner of the carrier $-21-$ a distance from the lower edge thereof $10-$ of corresponding to the distance between the stop $-29-$ and platen sections $-11-$ so that when the carrier $-21-$ is inserted through the guide passage $-27'$ with its lower end engaged with the stop $-29-$ the type plate will be in position between the inner faces of the platen sections $-11-$ and $-11'$ to permit the latter to transfer the impressions of the type plate onto both cards $-a-$ and $-a'$ when the jaws $-7-$ and $-7'$ are closed.

The type carrier $-20-$ is adjustable in its guide passage $-27'$ to bring its several type plates $-22-$ successively into a position between the platen sections $-10-$ and $-10'$ and thereby to permit the impressions of the type to be made upon both of the cards $-a-$ and $-a'$ when the jaws $-7-$ and $-7'$ are closed it being understood that each adjustment of the carrier $-20-$ will bring one of the plates $-22-$ into alinement with the plate $-23-$ of the carrier $-21-$ whereby the impressions of the alined plates will be made simultaneously upon both of the cards.

$35-$ Suitable means is provided for adjusting the carrier $-20-$ lengthwise one type-plate space at a time and for this purpose the upper end of the carrier is provided with a lateral offset $-20'$ carrying a pendant tooth $40-$ rack $-32-$ which is guided in a vertical opening $-33-$ in a guide block $-34-$ which is secured to the underside of the lid $-2-$ as is shown more clearly in Figures 4 and 7.

This tooth rack is engaged by a gear $45-$ $-35-$ which is secured to a rock shaft $-36-$, the later being journaled in suitable bearings in the block $-34-$ to extend through the end wall thereof to the exterior of the machine in alinement with the recess $50-$ $-5-$ of the base section $-1-$, the outer end of said shaft being provided with a hand crank $-37-$ by which it may be rocked upon its axis for effecting the vertical movement of the carrier $-20-$ through the medium of the rack $-32-$ and gear $-35-$.

In order that the positioning of the type plates $-22-$ of the carrier $-20-$ may be accurately determined the outer face of the rack $-32-$ is provided with a series of notches $-38-$ in spaced relation vertically corresponding to the spacing of the type plates $-22-$ and adapted to receive a holding pawl $-39-$ which is spring-urged inwardly by a coil spring $-40-$ as shown in $65-$ Figure 7, the upper and lower walls of the

notches $-38-$ being properly beveled to permit the plate $-20-$ to be removed or reinserted when desired, the outer side of the lower end of the rack $-32-$ being beveled at $-41-$ to facilitate the entrance of the rack into the guide opening $-33-$ past the pawl or detent $-39-$.

The lefthand bracket $-25-$ is provided with a vertical slot $-25'$ for receiving the lower edge of the offset portion $-20'$ of the plate $-20-$ and assisting in holding said plate against lateral movement, the lower wall of the slot $-25'$ being adapted to be engaged by the lower edge of the offset $-20-$ for limiting the downward movement of the plate $-20-$.

This type plate $-20-$ is normally in its extreme downward position so that its uppermost type plate $-22-$ will be registered with the platen sections $-11-$ but is adapted to be moved upwardly one type-plate space at a time when desired for successively registering the remaining type plates $-22-$ with the platen section $-11-$, this upward movement being accomplished by the forward and downward movement of the hand lever $-37-$ and corresponding rotation of the gear $-35-$ and resultant movement of the tooth rack $-32-$ upon which the plate $-20-$ is mounted.

During this step by step upward movement of the type plate $-20-$ the pawl $-39-$ will successively engage in the notches $-38-$ to produce a clicking sound and to frictionally hold the plate in its adjusted position, it being understood that the notches $-38-$ are spaced to the corresponding positions of the type plates $-22-$.

Suitable means is provided for limiting the upward movement of the type plate $-20-$ by the rotation of the shaft $-36-$ and for this purpose the hub as $-37'$ of the hand lever $-37-$ is provided with a shoulder $-42-$ adapted to engage a detent $-43-$ which is movable endwise in the outer end walls of the block $-34-$ and is yieldingly held in the path of the shoulder $-42-$ by spring $-43'$ as shown in Figures 1 and 2. The shoulder $-42-$ is arranged to engage the detent $-43-$ as soon as the lowermost type plate $-22-$ is brought into registration with the platen sections $-11-$.

If, however, it is desired to remove the type plate $-20-$ the detent $-43-$ may be tripped from its holding position by pushing it inwardly against the action of the spring $-43'$ out of the path of the shoulder $-42-$ thus permitting further forward and downward movement of the hand lever $-37-$ until the rack $-32-$ is disengaged from the gear $-35-$ thus permitting the type plate to be withdrawn upwardly by hand, as for example when it is desired to remove or replace the type plates.

Lid lock and release

While the type plate —20— remains in the machine with any one of its type plates —22— registering with the platen sections —11— the lid —2— of the housing will be locked in its closed position by means of a locking member —44— on the inner end of the rock shaft —36— engaging in a slot —45— in the upper end of the keeper plate —6—, see Figures 2 and 3.

The locking member —44— is preferably formed integral with the shaft —36— and consists of a segment of said shaft in that the portion thereof entering the slot —45— is cut away at —44'— so that its diametrical thickness will be slightly less than the open upper end of the slot —45— while the lower portion of the slot is of substantially the same radius as that of the locking member —44—.

As previously stated the keeper —6— is mounted on the base —1— while the shaft —36— having the locking member —44— is carried by the lid —2—. The locking member —44— and slot —45— are arranged so that when the lever —37— is adjusted to bring any one of the type plates —22— into registration with the platen sections —11— the wider part of the locking member —44— will be across the narrower part of the slot —45— to prevent opening of the lid but as soon as hand lever —37— is moved sufficiently to cause the shoulder —42— to pass the detent —43— a predetermined distance the locking member —44— will be adjusted edge-wise relatively to the narrower portion of the slot —45— to permit said lid to be opened.

This extra movement of the hand lever —37— to release the lid is controlled by an additional shoulder —42'— on the hub of the lever as shown in Figure 1, said shoulder —42— being adapted to engage the detent —43— to limit further movement of the hand lever —37— and thereby to indicate to the operator that the lid is free to open.

In Figure 3 the four positions of the hand lever —37— are shown by dotted lines for shifting the type plate —20— to a corresponding number of positions for successively registering the type plates —22— with the platen sections —11— as previously explained during which movements the locking member —44— will remain in interlocking engagement with the keeper —6— to hold the lid closed, but when the lever —37— is moved to engage its shoulder —42'— with the detent —43— the locking member —44— will then assume a position in the slot —45— to permit the lid to be opened.

Card stop and punch mechanism

The cards —a— and —a'— are fed by hand into the machine from the stop downwardly through the opening —16— in the lid —2—

until their lower edges engage an abutment —46— on the inner end of a plunger —47— which is reciprocally movable in a guide opening —48— in the block —34— transversely of the path of movement of the cards by and against the action of a retracting spring —49— shown more clearly in Figure 8, the abutment —46— being formed by cutting away the upper portion of the inner end of the plunger —47— thereby forming what may be termed a punch member —50— adapted to cut away corresponding portions of the lower lefthand edge of the cards at each inward movement of the plunger to enable the cards to be advanced one type line space after each punching operation on the same cards.

A relatively stationary shearing block —51— is secured in the block —34— just above the inner end of the abutment —46— and is provided with guide openings —52— in spaced relation to receive the lower ends of the cards for holding the same in operative position during the punching operation of the plunger —47—, the punch member —50— and shearing block —51— being preferably made of hardened steel for shearing co-action in removing the adjacent parts of the cards.

The punching operation of the plunger —47— is preferably controlled by one of the platen jaws as —7— and for this purpose said plunger normally extends rearwardly beyond the block —34— and is adapted to be engaged by a roller —47'— on the upper rear edge of the jaw —7— so that at each forward movement of the jaw —7— to its printing position a corresponding movement will be transmitted by said roller —47'— to the plunger —47— for effecting the cutting of the adjacent portions of the cards —a— and —a'—, the roller —47— being shown by full lines in Figure 8 and by dotted lines in Figures 5 and 9.

The rear end of the plunger —47— is provided with an upwardly extending radial pin —48'— having its upper end adapted to intermittently and automatically operate a feeding mechanism for the inking ribbon at each outward movement of the plunger in a manner hereinafter more fully described.

This punch and die —51— are located adjacent the lefthand edges of the cards so that when the cards are punched the remaining portions thereof will be free to move downwardly at the inside of the punch and die as required for effecting successive removals of portions of the adjacent edges of the cards in order to permit successive impressions of the type of both of the carriers —20— and —21— to be made simultaneously on the cards in transverse alinement and in sequence from the bottom upwardly.

These type impressions are adapted to be made upon both sides of the cards from both

ends thereof approximately one-half the length of the cards from either end and in order that the inward movement of the cards by hand may be automatically limited to approximately half the length thereof, I have provided a V-shaped stop —53—, Figure 9, the upper ends of the opposite sides of said V-shaped stop being secured to the inner faces of the opposed jaws —7— and —7'— near the under sides of the platens —9— as shown in Figure —9—, the opposite sides of the V-shaped stop —53— also serving as guides for the lower ends of the cards —a— and —a'—.

The V-shaped stop member —53— is preferably made of thin spring steel tensioned to automatically open when the jaws —7— and —7'— are opened and also serve to direct the inner ends of the cards into close proximity to opposite faces of the type plates —22— and —23— during the printing operation aided by the guide slots —52— in the shearing die —51—.

Additional card guides in the form of thin spring metal deflective plates —54— are secured at their upper ends to the lower inner sides of the guide rods —24— to extend downwardly therefrom at the outside of the guide plates —27— and at opposite sides of the type carrier —21— as shown in Figure 11 to deflect the lower ends of the cards slightly away from the inking ribbon as said cards are inserted into the machine, the lower ends of said deflecting plates —54— terminating above the printing lines between the type plates and platen sections —11— to permit the cards to be pressed into printing relation with the type as the jaws —7— and —7'— are closed.

40 Ribbon feed

The impressions of the type of both of the carriers —20— and —21— are preferably transferred to the cards through the medium of an inking ribbon —55— having its opposite ends wound upon suitable reels or spools —56— at the righthand end of the type carrier guides —27— and its intermediate portion extended laterally across and closely adjacent the outer faces of the guides —27— and around the lefthand ends thereof which latter are integrally united to form a rounding surface around which the ribbon may be free to travel.

In other words the intermediate portion of the ribbon is looped endwise around the outer faces of the guide members —27— so that its opposite sides may lie in planes parallel with and closely adjacent to the outer face of said guide members and therefore across opposite faces of the active type plates —22— and —23— of the carriers —20— and —21— between the platen sections —11— and —11'— of the jaws —7— and —7'—.

The reels —56— are mounted on suitable spindles —57— at opposite sides of the plane

and at the righthand end of the guides —27— as shown more clearly in Figures 5 and 6, said spindles being mounted on the lid —2— to extend downwardly therefrom as shown in Figure 5.

The portions of the ribbon —55— between the reels —56— and adjacent ends of the guides —27— are passed around suitable guide flanges —58— of rounding cross section, said guide flanges being arranged in transversely spaced relation corresponding approximately to the distance between the outer faces of the guide plates —27— to assist in holding the opposite sides of the ribbon in parallel planes and in close contact with said guide plates which latter serve to hold the opposite sides of the ribbon slightly out of contact with the adjacent faces of the type plates and assist in guiding and keeping the ribbon flatwise relatively to the type plates.

Additional guide plates —60— are secured to the lower edges of the guide plates —27— to extend upwardly therefrom across the lower edges and outer faces of the adjacent portions of opposite sides of the ribbon —55— to assist in holding said ribbon against sagging and also in close relation to the adjacent type plates, see Figures 10 and 11.

The guide plates —27— are provided with openings —61— and —61'— registering respectively with the upper and lower rows of type of the active type plate —22— of the carrier —20— to permit impressions of the type to be made upon the cards —a— and —a'— respectively through the medium of the adjacent sides of the ribbon —55— when the platen jaws are closed, said guide plates being also provided with openings —62— and —62'— registering respectively with the lower and upper row of type of the plate —23— of the carrier —21— as shown more clearly in Figure 11 to permit the impressions of each row of type to be made upon the corresponding card through the medium of the ribbon —55— when the platen jaws are brought to their printing positions.

The upper edges of the ribbon guides —60— and lower edges of the guide plates —27— are also spaced apart in alinement with the corresponding type of the type plates —22— and —23— to permit the impressions of said type to be impressed upon the cards —a— and —a'— through the medium of the ribbon —55— when the jaws are closed.

One of the reels as —56— is adapted to be rotated intermittently and automatically for winding the ribbon —55— thereon and simultaneously unwinding it from the other reel —56'— and for this purpose the upper end of the reel —56— is provided with a ratchet wheel —64— adapted to be engaged by a pawl —65— on one arm of a bell crank lever —66— which is pivoted at —67— to the un-

derside of the lid —2— as shown more clearly in Figure 6.

The other arm of the lever —66— is provided in its outer end with an elongated slot for receiving the pin —48— on the outer end of the plunger —47— whereby the return movement of said plunger by its retracting spring —49— after each operation of said plunger by the jaw —7— will cause the pawl —65— to operate the ratchet wheel —64— and corresponding ribbon reel —56— one tooth space at a time thereby effecting a corresponding shifting movement of the ribbon across the outer faces of the guide plates —27— and type plates —22— and —23—.

A holding pawl —68— is mounted upon a relatively short post —69— on the lid —2— for engaging the teeth of the ratchet wheel and holding the latter against reverse movement. This holding pawl —68— lies closely adjacent the ratchet pawl —65— and when it is desired to rewind the ribbon upon the reel as —56— both pawls —68— and —65— may be simultaneously tripped from engagement with the ratchet wheel —64— by means of a rock shaft —70— which is journaled in the lid —2— and is provided with a hand wheel or knob —71— by which it may be operated, said rock shaft being provided with a radially projecting pin —72— for engaging and tripping the pawls as shown more clearly in Figure 6.

This tripping of the pawls to permit the rewinding of the ribbon upon the reel —56— is best effected when the lid is in its closed position and the platent jaws brought to their printing positions at which time the roller —47'— will have moved the plunger —47— inwardly thereby operating the lever —66— to withdraw the pawl —65— out of engagement with the teeth of the ratchet wheel —64—.

When the ratchet wheel is released the reel —56— may be operated by hand through the medium of a hand wheel —73— which extends through an opening in the lid —2— as shown more clearly in Figure 1.

In order that the cards —a— and —a'— may be properly alined with the printing mechanism when inserted in the machine the lefthand edges of said cards are yieldingly held against the corresponding guide members —25— by yielding abutments —74— adapted to engage the righthand edges of the cards as shown more clearly in Figures 5 and 6, each abutment being provided with an outwardly projecting stem —75— guided in stop openings in a housing —76— which is secured to the underside of the lid —2—.

The abutments —74— and their stems —75— are spring pressed inwardly by coil springs —77— surrounding their respective stems shown more clearly in Figure 6. The guide opening for the plunger —47— is open at its front end to permit the discharge of

the punched out portion of the cards into a suitable receptacle —80— which is mounted within the base —1— directly under the front end of the guide opening as shown more clearly in Figures 8, 9 and 10, said receptacle being removable to permit the waste to be dumped when desired.

Operation

The operation briefly described is as follows:

Assuming that the lid —2— with the parts carried thereby are in their closed or operative positions after which the type carriers —20— and —21— will be placed in operative position within their respective guides, the carrier —20— being in its extreme down position thereby rocking the hand lever —37— to its extreme rearward position shown in Figure 1.

This latter operation brings the uppermost type plate —22— into registration with the platens —11— while the type plates —23— on the carrier —21— will be registered with the platen sections —11'—.

The cards —a— and —a'— are then inserted into the machine as illustrated in Figures 10 and 11 until limited by the engagement of their lower ends with the abutment —46— whereupon the hand lever —19— will be drawn forwardly and downwardly for bringing the platen jaws into printing co-action with said type plates for impressing the registering rows of type upon said cards near the lower edges thereof and at the same time the forward movement of the jaw —7— will cause its roller —47'— to engage and operate the plunger —47— for cutting away portions of the lower lefthand edges of the cards and permitting said cards to be advanced by hand into the machine a distance corresponding to the cut away portions ready for another printing operation in a line directly above that previously made.

These printing and cutting operations may be repeated as often as desired until practically one-half of the length of the card is printed after which the cards may be reversed end for end and the printing and cutting operations repeated on the remaining halves of the cards it being understood that each printing operation impresses the identification characters and dates in alinement upon corresponding portions of both cards.

If a card for a different borrower having a different identification character is to be used with the same dating characters the cards for that particular borrower will be inserted in the machine and the printing and cutting operation repeated in the manner described.

This first dating impression made upon the cards may be the date of issue or the date of return of the article to or from the borrower.

It will be noted upon reference to Figure 7 that the four type plates —22— on the carrier —20— bear different dates in sequence from the top downwardly and in this instance may represent the dates upon which the borrowed articles are to be returned it being understood that different books or other articles will be loaned for different time periods.

19 It therefore follows that if the date of return of one borrowed article is different from another the carrier —20— will have to be shifted by drawing the hand lever —37— forwardly to bring the proper type plate —22— into printing position after which the printing and punching operation previously described will be repeated.

When the use of the type plates —22— in the carrier —20— have been exhausted the carrier may be removed by simply pressing the pawl —43— inwardly and then rocking the lever —37— downwardly until its shoulder —42'— engages the pawl —43— whereupon the lid —2— may be raised and the carrier —20— withdrawn from the lid.

When the carrier —20— is withdrawn in the manner just described the plates —22— may be removed from the bottom downwardly and replaced by other plates after which the carrier —20— with the other plates therein may be replaced within the machine by simply pressing the same downwardly which will automatically return the lever —37— to its starting position, it being understood that when the lid is closed and the lever —37— restored to its first position the locking member —44— will be adjusted in its keeper —6— to lock the lid against opening movement.

40 The carrier —21— for the type plate —23— is preferably made of cardboard of about the same size and form as the cards —a— and —a'— and is retained in the public library for identification of a particular borrower to be used in the machine for impressing upon the cards —a— and —a'— the identification character of that particular borrower opposite the date of issue or return of the borrowed article.

50 That is, the public library carries in stock a considerable number of different identification type plates —23— so that one may be issued for each borrower to be retained in the library after each use.

55 It therefore follows that if the type plates —23— are made removable from the carrier —21— different type plates may be used with the same carrier while on the other hand if the type plates are fastened permanently to the carrier a corresponding number of carriers will have to be issued and retained in stock ready for use.

60 This identification card or carrier —21— preferably bears the name and address of the borrower and if desired may be used in

the machine in place of one of the cards —a— or —a'— to permit the dates of issue or return of the article to or from the borrower identified thereon in which case, however, the card —21— would be retained by the library authorities to be used sequentially by each borrowing or returning transaction.

70 As illustrated, one of the cards as —a— is provided with the title of the book or other article, the author and number of book and one of these cards is placed in each book to be loaned but is taken out of the book upon issue thereof to the borrower to be stamped in the machine with the borrowers identification character and date of issue or 80 return as previously explained.

75 Upon the issue of the book to the borrower another card as —a'— is stamped in the machine with the borrowers identification character and date of issue and then placed in 85 the pocket of the book to be retained therein until the return at which time it is again stamped with the date of return and identification character of that borrower to be used in the issue of other books to the same 90 borrower.

95 The operation of the other parts of the machine have been fully explained in the previous description and although the machine shown is particularly efficient in operation and adapted for a wide range of uses it is evident that various changes may be made in the detail construction and operation without departing from the spirit of the invention.

100 What I claim is:—

1. In a library card printing machine, opposed platens, a type carrier slidable at will to and from a position between the platens, means for guiding a card to be printed between the type of said carrier and one of the 105 platens a second type carrier slidable at will to and from a position between said card and platens, and means for bringing the platens into printing co-action with the type of both carriers for impressing said type upon the 110 card.

115 2. In a library card printing machine, opposed platens, a type carrier having a plurality of type plates mounted in sequence thereon, said type carrier being slidable at will to and from a position between said platens to successively register the type plates with the platens, means for guiding the card to be printed between the type of said carrier and one of the platens, a second type carrier slidable at will to and from a position between said card and platens, and means for bringing the platens and card into printing co-action with the type of both carriers.

120 3. In a library card printing machine, opposed platens, a type carrier slidable at will to and from a position between the platens and provided with type projecting from opposite faces thereof, means for guiding separate cards to be printed across opposite faces.

of the plate, and means for bringing the platens and cards into printing co-action with the type.

4. In a library card printing machine, opposed platens, a type carrier, a plurality of type plates mounted in sequence upon the carrier, means including a rack and pinion for adjusting the carrier to register each type plate with the platens, means for guiding the card to be printed across the printing face of the type, and means for bringing the platens and card into printing co-action with the type.

5. In a printing machine of the character described, a type carrier, a type-plate mounted on the carrier and provided with separate rows of type embossed therefrom in opposite directions, means for positioning separate cards to be printed across opposite faces of said type-plate to receive impressions of the type, and means for pressing said cards into printing co-action with the adjacent rows of type, said type carrier and cards being separately slideable at will to and from their printing positions.

6. In a printing machine of the character described, a type carrier, a type-plate mounted on the carrier and provided with separate rows of type embossed therefrom in opposite directions, means for positioning separate cards to be printed across opposite faces of said type-plate to receive impressions of the type, means for pressing said cards into printing co-action with the adjacent rows of type, and means between oppositely embossed type and the adjacent cards for transferring impressions of the type onto the corresponding cards.

7. In a printing machine of the character described, a housing comprising a base section, a lid section, cooperative platens mounted upon the base section in normally spaced relation, a type-plate carrier mounted on the lid section and movable therewith into and out of the space between the platens, and means for bringing the platens into printing coaction with the type-plate on the carrier.

8. In a printing machine of the character described, a housing comprising a base section and a lid section, in combination with a type carrier mounted on the lid to move therewith and having an independent movement relative to the lid, means for effecting said independent movement of the carrier, means for guiding a card to be printed across the face of the type, and means for bringing the card and type into printing co-action.

9. In a printing machine of the character described, a housing having separate guides arranged side by side and extending from the exterior to the interior of the housing, separate type-plate carriers slideable in said guides, each type-plate having embossed type projecting from opposite sides thereof in different lines, means for guiding cards to be

printed across opposite faces of the type-plates, and means for bringing the cards and type-plates into pressing co-action with the type-plates.

10. In a printing machine of the character described, a housing having a lid, a guide along which the card to be printed is adapted to be fed into the machine, means including a type carrier for making impressions upon the card, said type carrier having a plurality of rows of type arranged in sequence lengthwise of the guide, means for adjusting said carrier to present different rows of type to the printing point, and means controlled by the carrier-adjusting means for locking and releasing the lid in and from its closed position.

11. In a printing machine of the character described, a housing having a hinged lid adapted to be opened and closed, a type-carrier slideable in a guide opening in the lid and provided with a plurality of type-plates arranged edge to edge thereon, a platen movable into and out of printing co-action with the type of one of the plates, and means for adjusting the type-carrier along its guide to present different type-plates to the printing position, said lid having a card guide for directing the card to be printed between the type-plates and platen.

12. In a printing machine of the character described, a housing having a hinged lid adapted to be opened and closed, a type-carrier slideable in a guide opening in the lid and provided with a plurality of type-plates arranged edge to edge thereon, a platen movable into and out of printing co-action with the type of one of the plates, and means for adjusting the type-carrier along its guide to present different type-plates to the printing position, said lid having a card guide for directing the card to be printed between the type-plates and platen, and an additional type carrier slideable in a second guide opening in the lid and having its type in overlapping relation to the first-named card guide to cooperate with the platen for impressing its type upon the card.

13. In a printing machine of the character described, a housing having a hinged lid adapted to open and close, a printing couple including a type carrier slideable in a guide opening in the lid and having a plurality of type arranged in sequence thereon, means operable at will for adjusting the carrier endwise to bring different type to the printing position, and a lid-locking means controlled by the carrier-adjusting means for locking and releasing the lid in and from its closed position.

14. In a printing machine of the character described, a housing, a bar slideable vertically in a guide opening in the top wall of the housing and provided with rows of type arranged in sequence, one above the other, said

housing having its top wall provided with an additional guide opening for directing the card to be printed across the face of the type on said bar, a movable platen for impressing said card against the registering type on the bar, and means for adjusting said bar endwise to bring different type into registration with the platen.

15. In a printing machine of the character described, a housing, a bar slidable vertically in a guide opening in the top wall of the housing and provided with rows of type arranged in sequence, one above the other, said housing having its top wall provided with an additional guide opening for directing the card to be printed across the face of the type on said bar, a movable platen for impressing said card against the registering type on the bar, means for adjusting said bar endwise to bring different type into registration with the platen, and an additional type plate movable vertically in a guide opening in the top wall of the housing and having its type registering with a portion of the card and platen, whereby the operation of the platen will cause impressions to be made from the type-plate onto the card simultaneously with the impressions made by the type of the bar.

16. In a printing machine of the character described, a housing, a bar slidable endwise in a guide opening in the housing and provided with a plurality of type arranged in sequence from one end thereof, said housing having a card guide for directing the card to be printed across the face of the type on said bar, a platen movable toward and from the type on the bar for making impressions of the type on the card, a stop for limiting the movement of the card into the machine, and a rectilinearly movable punch actuated by the platen for punching out a portion of the card when the platen is moved to its printing position.

In witness whereof I have hereunto set my hand this 10th day of September, 1929.
LLOYD W. MOULTON.
